CLAIM

The ornamental design for a truck cap, as shown and described.

DESCRIPTION

FIG. 1 is a perspective view of the present design connected to a vehicle.

FIG. 2 is a perspective view of the present design.

FIG. 3 is a back elevational view of FIG. 2.

FIG. 4 is a front elevational view of FIG. 2.

FIG. 5 is a top elevational view of FIG. 2.

FIG. 6 is a bottom elevational view of FIG. 2.

FIG. 7 is a first side elevational view of FIG. 2; and,

FIG. 8 is a second side elevational view of FIG. 2.

The broken lines which define the bounds of the claimed design form no part thereof and are used to show environmental structure.

1 Claim, 6 Drawing Sheets
